UNITED STATES PATENT OFFICE.

JOHN W. WILLIAMS, OF BUFFALO, NEW YORK.

DESIGN FOR A CAMPAIGN-HAT.

SPECIFICATION forming part of Design No. 25,686, dated June 30, 1896.

Application filed April 11, 1896. Serial No. 587,229. Term of patent 34 years.

To all whom it may concern:

Be it known that I, JOHN W. WILLIAMS, of Buffalo, in the county of Erie and State of New York, have originated and invented a

5 new and useful Design for Campaign Hats; and I do hereby declare that the following is a full, clear, and exact description thereof, reference being had to the accompanying drawing, forming a part of this specification.

10 My invention consists of a new and original design for a hat and decorations specially intended to be worn by societies, clubs, or other bodies of individuals during conventions, parades, or other gatherings.

15 The figure of the drawing represents a perspective view of my design.

Referring to the drawing, 1 is the crown, which conforms in configuration with the shape of the head.

20 2 is the front of the hat, which consists of a flap integral with the crown 1. It occupies a substantially vertical position, its upper edge being rounded. The general configuration of the flap or front 2 is flat, as shown.

25 3 is the rear portion of the hat, and consists of a substantially vertical and flat flap similar in configuration to the front flap 2.

The front and rear flaps just described are considerably higher than the crown, and in

folding them, as shown, the side extensions 30 4 4 are formed, which are slightly inclined downwardly and substantially flat in configuration.

In one of the upper corners of the front flap 2 is secured a rosette consisting of the 35 central portion 5, surrounded by the fanciful border 6, leaving a space 7 blank, upon which may be placed a name or names.

8 8 are two streamers secured to the rosette and extending downwardly to a point near 40 the lower edge of the flap 2, as shown. Upon these streamers 8 8 may be placed names indicative of locality.

I claim—

The new and original design for a campaign-hat consisting of the crown 1, the front and rear portions or flaps 2 and 3, the side extensions 4, 4, the rosette 5, 6, 7 and the streamers 8, 8 all folded and arranged substantially as shown and described. 45 50

In testimony that I claim the foregoing as my own I affix my signature in presence of two witnesses.

JOHN W. WILLIAMS.
